METHOD OF MULTICOLORING A FABRIC

Charles Emmey, New York, N. Y.

Application March 19, 1936, Serial No. 69,689

13 Claims. (Cl. 41—33)

This invention relates to a method of multi-coloring a fabric and to a product thereof. More particularly, the invention relates to a method of delineating and multi-coloring a fabric to form an ornamental design for use as an applique emblem.

In the preparation of applique emblems and the like, the fabric material is cut or died out as a flat unitary piece which may be of a white or other color. The outline of the emblem being flat, is simple and crude not showing any multi-colored effect. If the emblem is made of white material a flat printing process is used for imparting a color surface. In such cases, the emblem has no appearance of surface unevenness to bring out in bold relief, its ornamental design.

It is one of the objects of this invention, to provide a simple, effective and relatively inexpensive method of making a configuration and delineating a fabric, and then multi-coloring certain areas of said fabric, to impart an ornamental appearance to the fabric.

It is another object of the present invention to provide a method of forming a configuration on a fabric, delineating certain portions of the configuration, and multi-coloring the same while adhering the configuration onto wearing apparel, in a simple and effective manner.

It is another object of this invention to provide a novel method of making an article of manufacture having a delineated area with colors on certain portions of the area to impart an ornamental appearance thereto.

It is one further object of this invention to provide a method of forming an applique emblem of decorative and soft uneven surface, provided with a delineated area imparting a bold relief effect to the surface thereof.

With the above and other objects in view, the various features of the invention will be apparent from the detailed description of a preferred embodiment hereinafter given.

The invention preferably includes the method of outlining a design or making a configuration on a fabric by delineation, then applying a multi-colored transfer strip, over the delineated area to correspond therewith, and applying suitable heat and pressure on the strip whereby certain sections of the delineated area are colored to impart a relief appearance to the fabric.

In the drawing:

Fig. 1 is a plan view of a delineated applique;

Fig. 2 is a plan view of a transfer strip having a multi-colored outline for laying over the applique;

Fig. 3 is a plan view of the applique with the strip overlay, showing corresponding placement thereon;

Fig. 4 is a plan view of applique after the multi-coloring operation.

Figure 5 is a section taken along lines 5—5 and looking in the direction of the arrows thereof, of Fig. 3 showing the applique ready to be colored; and,

Fig. 6 is a sectional view, showing the operation of multi-coloring the applique, and of joining the same to a wearing apparel in one operation.

Referring to the drawing in which similar reference characters relate to like parts throughout, a color receptive fabric 10, is cut out into any desired outline depending upon the type of design to be made. For purposes of illustrating the present invention, the fabric as shown is an applique having the outline of an elephant which contains certain delineated areas effected by any suitable means, preferably by an embroidering stitch 11. The purpose of the stitch in from the contour of the fabric is to effect a natural outline and relief to the fabric in which the limbs and other parts of the elephant are more boldly delineated. Also certain areas of the emblem are delineated, for example as shown in the present illustration at 12 to permit coloring of this area. Such area will have by the present method a different color from the remainder of the delineated area.

After the area of the outline is delineated, certain parts thereof are colored as desired. This coloring is effected by means of a carrier strip 13, having on one side a plurality of colors or pigments 14 and 15 respectively. Each of the colors has an area corresponding with the respective area of the delineated fabric or applique. In the present instance color 14 is red and color 15 on the strip is brown.

The carrier strip 13 is made preferably of paper having a glassine or glazed surface and a rough under surface for carrying pigments 14 and 15 as shown in Fig. 2. The pigments are well known in the art and are mixed with a suitable vehicle such as paraffin wax or beeswax which is easily fusible at temperatures of about 125° and 250° Fahrenheit, depending on the amount of pigment added. Said pigments are incorporated with the melted wax and applied to the under surface of strip 13 while in a plastic condition, and allowed to dry thereon.

In order to transfer the colors to the applique, strip 13 is laid over the applique so that the

outlines thereon of the colored portions are within corresponding delineated areas of the applique as shown in Fig. 3. Suitable heat and pressure are then applied over the strip whereby colors 14 and 15 are melted and transferred to the surface of the applique imparting thereto a multi-colored effect. Very slight heat and pressure are necessary in such color transfer operation, and in order to accomplish said operation, 5 10 15 10 an ordinary hot flat iron is used. The temperature should not exceed 250° Fahrenheit, and the pressure applied is the weight of the iron. The transfer operation is almost instantaneous because of the relatively low melting point of the 15 colors 14 and 15.

The heat and pressure of the ordinary flat iron when applied over the transfer strip as shown in Figures 3 and 5 cause the pigments or colors to penetrate the surface area of the applique 10 20 without scorching or injuring the same.

In the present illustration it will be noted that the applique is colored red and brown leaving an intermediate uncolored area 12 shown in Fig. 4, thus imparting to the applique a three-colored 25 25 effect pleasing to the eye and attractive. Also, the color does not pass beyond the delineations as shown in the drawing.

By the present method the applique may be simultaneously colored and applied to a wearing 30 35 30 garment. The applique has a coating 16 on its underface, made of any thermoplastic material such as vinyl acetate or chloride with a suitable plasticizer such as dibutyl phthalate and the like. The applique is placed over any desired part of 35 40 35 wearing apparel 17 as shown in Fig. 6 whereupon carrier strip 13 is laid over the applique so that the outline thereof corresponds with that of the applique. Upon application of the heat and pressure of a hot iron the color is transferred 40 45 40 from strip 13 to the applique so that the outline thereof corresponds with that of the applique. At the same time the film 16, of thermoplastic material penetrates the wearing apparel forming a permanent union therewith.

45 While the above method has been described with reference to an applique having the appearance of an elephant, it is to be noted that the invention includes any applique of ornamental outline on the surface of which there are several 50 55 delineated areas. Any or all of said areas may be multi-colored to impart a natural appearance to the applique. Furthermore, the applique may be of any outline such as of a flower, circus animal, flag, or other decorative appearing article.

The invention, furthermore, includes any applique made of felt or like material having a plurality of delineations on its surface, the confines of several of the delineations being colored to impart an ornamental effect thereto. The surface of said applique is uneven having the effect of an outline in bold relief due to the multi-color effect. The delineations are made on the applique by any suitable means such as by pressing dies having sharp outlines, on the face of the applique without cutting into the same, or by embroidering the different areas of the outline to locate boundaries within which different colors are to be placed.

70 Changes as to form, appearance, use of materials, methods of arrangement of parts and outlining of delineations on the surface of the materials may be made without departing from the spirit and scope of the invention.

75 I claim:

1. The method of ornamenting a fabric and like material which consists in preforming an ornamental outline thereon, applying a strip carrier, having an outline of colored material thereon, onto the outline on the fabric so as to correspond in configuration therewith, and finally applying suitable heat and pressure on the carrier whereby the color is transferred to the fabric within the limits of the outline on the fabric. 5

2. The method of ornamenting a surface which 10 consists in preforming a sketch thereon, forming intermediate delineations on the sketch applying a carrier having transferable variegated colors on one face forming an outline corresponding with the sketch, applying heat and pressure to 15 the carrier whereby the colors are transferred to the surface to color desired parts of the sketch, and finally removing the carrier therefrom whereby a pictorial colored design is obtained on the sketch. 20

3. The method of ornamenting applique emblems which consists in impressing a sketch on the emblem, laying a strip of variegated color material over said sketch to correspond therewith, and applying heat and pressure whereby 25 25 the color material passes from the strip to the emblem and within the confines of the sketch to obtain a design of colored effect.

4. The method of ornamenting applique emblems having an uneven surface which consists in 30 preforming a sketch thereon having an outline by means of embroidering, applying a carrier strip having variegated colors thereon forming an outline corresponding with that of the emblem, subjecting the strip to suitable heat and pressure 35 whereby the colors are transferred to the emblem and finally removing the strip.

5. The method of decorating an applique emblem of fabric which consists in making a desired sketch on the fabric by embroidering to 40 45 40 impart the design in bold relief and as an uneven surface, laying a strip on the fabric, having a transferable multi-colored outline thereon corresponding with the sketch of the fabric, applying suitable instantaneous heat and pressure on the strip whereby the colored part of the strip coats the corresponding part of the sketch, and finally removing the strip.

6. The method of decorating fabric material which consists in making a configuration on said 50 55 material, delineating limited portions of the configuration to obtain an uneven surface thereof, and then applying variegated colors within desired limited portions of the material to impart a multi-colored effect to the fabric. 55

7. The method of decorating applique material, which consists in making a configuration on the material, embroidering desired intermediate portions in the configuration to bring out details in the configuration laying a strip having removable 60 colors thereon over the configuration, and applying suitable heat and pressure to the strip whereby the colors are received within the corresponding intermediate portions of the material.

8. The method according to claim 7 in which 65 the intermediate portions are delineated, and the configuration is cut out from the remainder of the material.

9. The method of decorating fabric material forming applique emblems which consists in forming a configuration in said material, delineating certain desired areas of the configuration to bring out the details of the configuration, applying different colors to the areas by overlaying a strip having colors thereon in corresponding areas, and 70 75

subjecting the strip to heat and pressure, and finally removing the strip to obtain a multi-colored emblem.

10. The method of decorating an applique emblem, which consists in forming a configuration by reinforcing the outline thereof, delineating certain limited areas within the configuration by means of an embroidering stitch whereby to receive color coatings on said areas, and simultaneously applying a plurality of colors on certain 10 of said areas within the configuration to impart a decorative appearance thereto.

11. In the making of decorative applique emblems, the steps including cutting a configuration from fabric material, reinforcing the edge of said configuration, embroidering certain intermediate portions of the configuration to bring out the details more boldly and to form an uneven surface thereof, laying a strip carrying 20 variegated color pigments thereon over corresponding limited portions within the configuration, and finally applying heat and pressure to the strip whereby the pigments coat certain of said portions and impart a multi-colored effect 25 to the configuration simulating a natural object.

12. In the method of decorating applique emblems, the steps which comprise cutting a decorative outline from a fabric or like material, embroidering said outline to impart a bold effect to the appearance thereof, delineating intermediate parts of the surface of the outline to bring out said parts in bold relief, and finally applying colors on the intermediate parts by means of simultaneous heat and pressure. 5

13. In the method of decorating applique emblems, the steps which consist in cutting a decorative outline from fabric and the like, making intermediate delineations on the surface of the outline to bring out in bold relief the decorative- 15 ness of the outline and its surface, overlaying a carrier strip having variegated colors on intermediate parts thereof forming an outline corresponding with that of the outline, and finally applying simultaneous heat and pressure on the 20 transfer strip whereby the coloring thereon is transferred over corresponding intermediate delineated parts of the face of the fabric outline imparting a decorative appearance thereto.

CHARLES EMMEY. 25
